Primary Examiner — Martie K Holtje(74) *Attorney, Agent, or Firm* — Knobbe Martens Olson & Bear, LLP(57) **CLAIM**

The ornamental design for a watch, as shown and described.

DESCRIPTION

FIG. 1 is a front perspective view of a watch showing an embodiment of the new design;

FIG. 2 is a front elevational view thereof;

FIG. 3 is a rear elevational view thereof;

FIG. 4 is a right side elevational view of thereof;

FIG. 5 is a left side elevational view of thereof;

FIG. 6 is a top plan view of thereof; and,

FIG. 7 is a bottom plan view of thereof.

The dot-dash-dot broken lines in FIGS. 1 and 2 around the face of the watch denote unclaimed boundaries of the claimed design, and the dash-dot broken lines in the Figures show portions of the watch which form no part of the claimed design.
